UNITED STATES PATENT OFFICE.

ROBERT H. HACKNEY, OF MILWAUKEE, WISCONSIN, ASSIGNOR TO PRESSED STEEL TANK COMPANY, OF WEST ALLIS, WISCONSIN, A CORPORATION OF WISCONSIN.

METAL BARREL.

1,178,717.

Specification of Letters Patent. Patented Apr. 11, 1916.

Application filed December 5, 1913. Serial No. 804,793.

To all whom it may concern:

- Be it known that I, ROBERT H. HACKNEY, a citizen of the United States, residing at Milwaukee, in the county of Milwaukee and 5 State of Wisconsin, have invented certain new and useful Improvements in Metal Barrels, of which the following is a specification, reference being had to the accompanying drawing, forming a part thereof.
- 10 This invention relates more particularly to metal barrels the heads of which have depressed or inwardly bent central portions and outwardly bent marginal rims forming chimes.
- 15 The main objects of the invention are to prevent rain or water caught or held in the depressed portion of the upper head, when the barrel is stood on end and the bungs withdrawn, from flowing into the barrel 20 through the open bung holes; to facilitate completely drawing the contents from the barrel; and generally to improve the construction and increase the utility of barrels of this class.
- 25 It consists in certain novel features of construction as hereinafter particularly described and pointed out in the claims.

In the accompanying drawing like characters designate the same parts in both figures.

Figure 1 is an axial section on the line 1—1, Fig. 2, of a portion of a metal barrel embodying the invention, the middle portion of the barrel being broken away to 35 show the heads on a larger scale in condensed space; and Fig. 2 is a plan view of the upper head, or the head having the bung holes.

The body *a* of the barrel may be drawn or 40 pressed, as shown in Fig. 1, integrally with one head *b*, from steel or other metal, or may so far as the present invention is concerned, be otherwise constructed, the head *b* being preferably formed with an outwardly projecting rim forming a chime *c* at one end of the barrel. The other head *d* of the barrel, which may be made separate 45 from the body and fitted and secured in the open end thereof, as shown or otherwise, is formed with an outwardly projecting marginal rim or chime *e*, like or similar to the chime *c*, and adjacent to opposite sides of the barrel, with outwardly pressed bosses *f* and *g*, of about the same 55 extent outward as the chime *e* with which

they merge, as shown in both figures of the drawing. In these bosses are formed openings which are preferably provided with metallic bushings *h* and *i*, fitted and secured therein, and projecting outwardly therefrom beyond the rim or chime *e*, as shown in Fig. 1. The outer ends of the bung holes which are formed in these bushings are thus carried outwardly beyond the plane of the outer edge or highest part of the chime. The bosses may be formed in either head of the barrel, but are more conveniently and preferably formed in the head *d*, which is made separate from and secured in the open end of the body. In the use of barrels of this kind, they are often stood on end out of doors, with the bungs in the upper head, and rain or water is very apt to be caught or held in the depressed central portion of the head surrounded by 60 the chime, so that if the bungs are removed, the water or other liquid held in the head, will drain into the barrel, cause corrosion, and contaminate its contents, unless great care is exercised, or provision is made in 65 the structure of the barrel to prevent it.

The provision of the barrel head with outwardly projecting bosses for the bushings in which the bung holes are formed, as herein shown and described, effectively 70 prevents without care or attention water or other liquid caught in the upper head of the barrel, from draining into it through the bung holes when the bungs are removed. These bosses forming cavities on 75 the inner side of the head also provide for and facilitate completely draining the contents of the barrel therefrom, one of the bung holes serving as a vent to permit air 80 to enter the barrel while the contents are being drawn through the other bung hole, and the outwardly pressed chime *e*, forming on the inner side of the head a channel 85 which communicates with and drains into the cavity of the boss on the lower side of the barrel when it is tilted or held with the head *d* downward for drawing the contents 90 therefrom.

I claim:

1. A metal barrel having a peripheral 105 chime projecting outwardly beyond the central portion of the adjacent head, which is formed adjacent to opposite sides of the barrel with outwardly projecting bosses having bung holes the outer ends of which 110

are outside of the plane of the overhanging edge of the chime.

2. A metal barrel having a peripheral chime projecting outwardly beyond the central portion of the adjacent head and forming an internal channel, the head being formed adjacent to opposite sides of the barrel with outwardly projecting bosses having bung holes the outer ends of which are

outside of the plane of the overhanging edge of the chime and forming internal cavities with which said channel merges.

In witness whereof I hereto affix my signature in presence of two witnesses.

ROBERT H. HACKNEY.
